UNITED STATES PATENT OFFICE.

JAMES J. G. COOPER, OF JACKSONVILLE, FLORIDA.

TOY CARTRIDGE.

1,311,950.

Specification of Letters Patent.

Patented Aug. 5, 1919.

Application filed February 13, 1919. Serial No. 276,792.

To all whom it may concern:

Be it known that I, JAMES J. G. COOPER, a citizen of the United States, residing at Jacksonville, in the county of Duval and State of Florida, have invented certain new and useful Improvements in Toy Cartridges, of which the following is a specification.

This invention relates to games and toys, and more especially to aerial projectiles; and the object of the same is to produce a toy cartridge carrying its own bullet and ejecting means and capable of being inserted into a toy gun or cannon and fired and then withdrawn and reloaded.

I prefer to use as the ejector a spring and in the present case I employ an expansive coiled spring, while in a companion case filed herewith (Serial Number 266,791) I employ a contractile spring of rubber.

The present case is designed to protect the specific form of my invention broadly illustrated in the accompanying drawings, and in which—

Figure 1 is a side elevation;

Fig. 2 a longitudinal section, and

Fig. 3 is a cross section of the projectile only, taken on the line 3—3 of Fig. 1.

I will say at starting that I desire the broadest interpretation given to the terms used herein and do not wish to confine myself to the shape, size, proportion, or materials of parts. Generally speaking the invention comprises a cartridge shell, a bullet or projectile proper, the ejector which in the present case is a spring, and retaining means for holding the spring under tension and for releasing it at will to fire or eject the bullet.

The shell is herein shown as a cylinder having a tubular body T and an exterior flange F at its rear end, the body being longitudinally slotted at T' just forward of the flange for a purpose to appear. The bullet has a head H which may be pointed at the front but is enlarged at the rear into a shoulder H' which rests normally against the front end of the shell, and from the rear end of the bullet a shank S extends into the bore of the shell and is headed or offset as at O at its rear end which stands normally about midway the length of the shell. The ejector in the present case is a coiled wire spring E connected near its rear end with the shell by means of a transverse pin P, while the front end of the spring rests against the head or offset O, and in the nor-

mal position of the latter the spring is under tension. The retaining means for holding the bullet within the shell and the spring under pressure consists in the present case of a short lever R pivoted at R' within the slot T' and hooked at its front end as at R'' so as to engage the offset O as seen in Fig. 2, and the rear end of this retainer may have a handle R''' by means of which it can be manipulated, although in any event it projects beyond the flange F and can be actuated mechanically or manually.

To load the shell, the offset O at the rear end of the shank S is passed into the front end of the shell, and the entire bullet pressed to the rear until the shoulder H' contacts with the shell as seen in Fig. 2. Meanwhile the retainer is moved so that its hook R'' permits the passage of the head O, and eventually the retainer is pressed inward at its forward end so that the hook engages the offset just at a time when the ejector spring E is under compression. The entire cartridge may now be inserted into the rear end of a toy gun indicated in dotted lines at G in Fig. 1. To fire the cartridge it is only necessary to actuate the retainer so as to disengage its hook from the offset. This can be done mechanically or manually. The user can pull down on the handle or push down on the projecting rear end of the lever R until the hook R'' clears the head O and immediately the spring ejector E expands and acts to shoot the bullet from the shell and out the bore of the gun in a manner which will be clear. The shell may now be withdrawn from the breech of the bore and replaced by another which is loaded.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention what I claim as new and useful and desire to secure by Letters Patent is:—

1. A cartridge comprising a shell open at the front and having a slot in its wall, a bullet having a shank extending into the shell and offset at its rear end, ejecting means within the shell contacting at its front end

with said offset and connected at its rear end with the wall of the shell, and retaining mechanism movably mounted within said slot and adapted to engage in front of said offset.

2. A cartridge comprising a shell open at both ends and having a slot in its wall, a bullet having a shank extending into the shell and offset at its rear end, ejecting means within the shell contacting at its front end with said offset and connected at its rear end with the wall of the shell, and a retainer pivotally mounted within said slot and having a hook at its front end to engage said offset, its rear end extending out of the rear end of the shell.

3. A cartridge comprising a tubular shell having a longitudinal slot in its body and an exterior flange around its rear end, a bullet having a head at its front end to rest against the front end of the shell, a shank leading to the rear from said head, and an offset portion at the rear end of the shank, an ejecting spring within the shell behind said offset, and a lever pivoted between its extremities within said slot and having a hook at its front end to engage said offset and its rear end projecting to the rear of said flange, for the purpose set forth.

4. A cartridge comprising a tubular shell having a longitudinal slot in its body and an exterior flange around its rear end, a bullet having a head at its front end to rest against the front end of the shell, a shank leading

to the rear from said head, and an offset portion at the rear end of the shank, a coiled expansive spring located within the shell with its front end resting against said offset, a pin through the shell and the rear portion of said spring, and a retainer pivoted within said slot and having a hooked front end adapted to engage said offset and its rear end projecting beyond said flange, for the purpose set forth.

5. A cartridge comprising a tubular shell whose wall is slotted throughout its rear portion, and an external flange around the rear end of the wall, a bullet whose head is adapted to lie against the front end of the shell, the head having a shank projecting into the shell and offset at its rear end at a point opposite the forward portion of said slot, a coiled expansive spring disposed within the shell with its front end bearing against said offset, a pin through the shell and the rear portion of the spring, a lever pivoted between its ends within said slot, its front end having a hook detachably engaging said offset and its rear end projecting beyond said flange, and a handle attached to said rear end.

In testimony whereof I affix my signature in presence of two witnesses.
